TAPE CONTROL MECHANISM

Frank E. Anderson, Brooklyn, N. Y.

Application January 19, 1937, Serial No. 121,327

8 Claims. (Cl. 271—2.3)

This invention relates to apparatus for controlling the movement and storage of printed news bearing tape, otherwise known as a tape control mechanism or tape feed device. It is particularly adapted for use in association with news recording machines including printing telegraph machines; it may be used specifically in combination with a standard stock ticker using standard paper tape.

10 News projecting machines heretofore used have employed an electric motor operating on a start-stop basis. Such devices are always a considerable number of quotations behind the stock market, so that if at any moment the printing mechanism stops for any reason, a large number of quotations recorded on the tape remain undisplayed until after the machine resumes operation.

The objects of this invention include: a tape 20 control mechanism which can be combined with any standard tape machine of any kind employing either paper or any other form of tape, such for example as the standard stock ticker; a highly sensitive variable speed mechanism for arresting the motion of the news bearing tape or sheet 25 when the news recording machine stops printing; reducing the delay between the recording and displaying of a news item; elimination of all unnecessary mechanism; simplicity of operation; 30 economy in cost of construction; reducing the number of stock tickers required; the employment of but a single tape for recording, projecting and reference purposes; a portable tape control mechanism adapted to be readily associated 35 with or dis-associated from a standard tape machine or stock ticker. Other objects will appear from the detailed description which follows.

In accordance with this invention the tape or sheet carrying the recorded news, is drawn by a 40 drawing roller over a control roller which rotates in sliding contact with the tape, said drawing roller and control roller being normally actuated by a common drive shaft which is driven continuously, but when any slack in the tape has been 45 taken up, the increased tension of the tape arrests the further rotation of the control roller, thereby rendering said control roller and the drawing roller inactive relative to the continuously driven shaft, whereby the further movement of the tape is arrested until the renewed 50 operation of the news recording machine removes tautness from the tape, whereupon the drawing roller and the control roller are immediately re-connected to the continuously driven drive shaft, 55 to cause the drawing roller to at once resume

the tape drawing or tape winding movement. The drawing roller is geared to draw the tape at a speed not less than the maximum delivery speed of the news recording machine. Under normal conditions of operation therefore, the 5 tape may be said to be semi-taut rather than slack, and this semi-taut condition of the tape operating against increased spring tension, tends to arrest the motion of the control roller and hold it in a position to effect instantaneous disconnection of the drive shaft. When the news recording machine is operating at maximum output, as for example in printing market closing prices on a stock ticker, the tape is running free, and therefore has less tendency to arrest the motion 10 of the control roller. Under these conditions the control roller travels away from the instantaneous disconnect position, until a reduction in speed of operation of the news recording machine causes the tape to apply progressively increased 15 tension upon the control roller, whereby the motion of the control roller is retarded against increased spring tension as said roller once more approaches the disconnect position.

In the drawings comprising four sheets of four- 20 teen figures numbered Figs. 1 to 5 inclusive, and 5a to 13 inclusive, certain embodiments of the invention are illustrated.

Fig. 1 is a front elevation of one form of my tape control mechanism associated with news recording and projecting apparatus.

Fig. 2 is a plan view of the tape control mechanism and drive motor shown at the left of Fig. 1.

Fig. 3 is a side view of the same.

Fig. 4 is a detailed end view of a portion of 35 the mechanism of Fig. 3, looking from the right of said figure.

Fig. 5 is a vertical sectional view of the actuating mechanism.

Fig. 5a is an end view taken along the line 40 5a—5a of Fig. 5, looking in the direction of the arrows.

Fig. 6 is a plan view of a detail.

Fig. 7 is a side view partly in vertical section taken along the line 7—7 of Fig. 6, looking in the 45 direction of the arrows.

Fig. 8 is a perspective view of a modified form of the device of Fig. 6.

Fig. 9 is a plan view of my tape control mechanism mounted in portable compact form. 50

Fig. 10 is a side view of the same.

Fig. 11 is an end view of a modified form of my tape control mechanism.

Fig. 12 is a central vertical section of the same; and

Fig. 13 is a sectional view taken along the line 13—13 of Fig. 12, looking in the direction of the arrows.

Like reference characters designate corresponding parts throughout the several figures of the drawings.

Referring first, generally, to the structure shown in Figs. 1 to 5a inclusive. A news recording machine 20 is shown at the right of Fig. 1. 10 Machine 20 may be any one of the many devices now in use for the electrical transcription of messages. For purposes of illustration it will be assumed that machine 20 is a standard stock ticker adapted to record stock quotations upon a 15 tape 21, which will be advanced by an intermittent step by step movement from the right of Fig. 1 and fed through suitable projecting apparatus shown at the center of Fig. 1 to the tape control mechanism shown generally at the left of 20 that figure.

After the news recorded on tape 21 has been projected it may either be stored upon winding reel 38, or fed into a suitable receptacle such as a waste basket as hereinafter more fully described. After leaving stock ticker 20, tape 21 passes over upper guide roller 70, then back around lower guide roller 23, to form an S curve, thence along tape guideway 86 (Fig. 9), running parallel with reflecting mirror 27 (Fig. 1), beneath projector lens 26. A suitable light source 28 illuminates tape 21. When tape 21 is translucent, light source 28 may be positioned beneath the tape, but when stock ticker 20 uses standard paper tape, the projector mechanism 35 will be operated on the principle of opaque projection. It should be understood however, that as the projector mechanism forms no part of the present invention, any preferred form of projecting mechanism, adapted to operate to project recorded news, may be used in conjunction with news recording machine 20.

The tape control mechanism is operated by a suitable continuously driven prime mover 29, in this case an electric motor. In passing through the tape control mechanism, tape 21 is kept taut in any preferred manner as by a drawing roller 74 (Fig. 3), driven by gear driven shaft 49. To prevent smudging of the symbols recorded on tape 21, guide roller 23 may be provided with one or more suitable spacing collars 31 (Fig. 9), adapted to space the tape from the surface of the guide roller. Tape 21 now passes over rotatable sleeve or thimble 59 (Fig. 2), then around direction changer 33, between tape drawing roller 74 (Fig. 3) and spring arm roller 37, to winding reel 38, or, if tape 21 is not to be stored and kept as a permanent record, the tape after leaving tape drawing roller 74 and spring arm roller 37 may be allowed to feed by gravity (Fig. 10) 60 into a waste basket (not shown). Roller 37 is rotatably mounted upon a suitable arm 36, the roller being pressed against the tape by the action of a coiled spring 35 (Fig. 2).

The drive shaft 50 of the tape control mechanism, is continuously driven from motor 29 and its associated groove pulley 42 mounted on the motor shaft by means of motor belt 43 which drives gear box pulley 44. Winding reel 38 is indirectly driven from groove pulley 44 associated with gear box 47 by means of driving belt 49 which is connected to groove pulley 39 of winding reel 38. The shaft (not shown) of winding reel 38, is supported in a bearing 46 which is in turn supported by a bracket 45 mounted 75 upon the casing of gear box 47 (see Figs. 2, 9

and 10). Winding reel 38 is provided with a removable reel head 80, which is detachably secured to the core of reel 38 by spring tensioned thumb screw 81.

The mechanism for feeding the tape intermittently is best shown in Figs. 5 and 5a. Gear 48 is mounted on a shaft 49 within gear box 47. It is driven from gear box pulley 44 by means of the continuously driven shaft 50 and worm 53. Drive shaft 50 is rotatably mounted in sleeve 10 bearings 51 and 54. Bearings 51 and 54 are in turn locked in proper position in the gear box casing by means of set screws 52 and 55 respectively.

Main spring 56 is mounted upon drive shaft 50 in such a manner that under normal conditions, spring 56 grips drive shaft 50 with sufficient tension to rotate with the shaft. Spring 56 is so designed, however, that when counter-tension is applied to one end of the spring, its grip upon drive shaft 50 is released, and the drive shaft will now turn freely on its axis, while main spring 56 will remain stationary. Referring to Fig. 5, the left hand end of main spring 56 is anchored in a hole drilled in the right hand end of worm 53; and the right hand end of main spring 56 is similarly anchored in a hole 69 drilled in the face of collar 58 (Figs. 5 and 5a), abutting the end of the sleeve bearing 54. Collar 58 is rotatably mounted on drive shaft 50, and when main spring 56 is under normal tension, drive shaft 50, main spring 56, worm 53 and collar 58 revolve in unison, but when collar 58 is prevented from revolving, it immediately applies sufficient counter-tension to main spring 56 to cause the main spring to disengage drive shaft 50, and main spring 56 and worm 53 immediately stop turning, thus bringing gear 48 to a stop. Drive shaft 50, however, is driven continuously by motor 29 (Fig. 2), by way of pulleys 42 and 44, and belt 43. The tape control roller clutch mechanism indicated generally by reference numeral 57 (Fig. 5), includes collar 58, sleeve or thimble 59, adapted to rotate with collar 58, auxiliary spring 60, and anchoring pin 68, rotatably mounted on a shaft 66, which is mounted upon a supporting bracket 65. The end of shaft 66 is secured to bracket 65 in any suitable manner as by riveting. Shaft 66 may be provided with a head 64 turned from the same piece of metal. To reduce friction between the shaft and thimble 59, a ball race 63 may be provided. Anchoring pin 68 is mounted upon a washer 62. Washer 62 is in frictional engagement and rotatable in unison with, thimble 59. The opposite ends of auxiliary spring 60 are detachably anchored by looping one end about anchoring pin 68, and the other end may be similarly looped about anchoring pin 61 which is secured in the end face of collar 58. Auxiliary spring 60 is rotatably mounted upon shaft 66, while pin 68 guides in cam slot 67 of collar 58 (Fig. 5a). Main spring 56 and auxiliary spring 60 are oppositely wound. As shown in Fig. 5, main spring 56 is a left hand spring, or is wound counter-clockwise, while auxiliary spring 60 is a right hand spring, or is wound clockwise. When thimble 59, washer 62, pin 68, auxiliary spring 60, collar 58, main spring 56, and drive shaft 50, are revolving as a single unit, the momentum gained by thimble 59, tends to advance washer 62, until anchoring pin 68 approaches the leading end of cam slot 67, substantially as indicated in Fig. 5a. This is the position of the several parts when due to slackness in the tape, thimble 59, over which the tape 75

"rides", is revolving. When tape drawing roller 14 (Fig. 3), removes slackness from tape 21, the tape becomes taut and "hugs" a larger portion of the surface of thimble 59 to apply increasing braking pressure on the thimble, which gradually loses momentum and finally stops. As thimble 58 carrying washer 62, anchoring pin 68, and auxiliary spring 60, loses momentum, it lags "behind" collar 58 and main spring 56 driven by main drive shaft 50, and the leading edge of cam slot 67 moves "ahead" of anchoring pin 68, until said pin approaches the trailing edge of cam slot 67. In this position, anchoring pins 68 and 61 are brought closer together, against the increased tension of auxiliary spring 60. This increased tension of auxiliary spring 60, tends to apply counter-tension to main spring 56 through collar 58, to which main spring 56 is anchored at 69, until the increased tension of auxiliary spring 60, acting through collar 58 against the normal tension of main spring 56, disengages main spring 56 from the main drive shaft 50; and main spring 56 and worm 53 stop revolving, and gear 48 comes to rest. When pressure is removed from thimble 59, main spring 56, and auxiliary spring 60, seek to resume normal tension, and in dissipating their stored energy, the springs tend to force anchoring pin 68 along cam slot 67, in a direction away from anchoring pin 61, until the energy stored by main spring 56 under counter-tension, is dissipated sufficiently to permit main spring 56 to re-engage drive shaft 50, thus revolving spring 56, worm 53, gear 48, and collar 58, auxiliary spring 60, washer 62 and thimble 59.

A compact self contained tape control mechanism is shown, by way of illustration in Figs. 9 and 10. The projector and news recording machine are omitted. Metal base 82, supports motor 29, the tape control mechanism, and the reflecting mirror of the projector apparatus. Base 82 allows ample space for the projector apparatus. Motor 29 is supported upon a rubber mat 83. Gear box 47 may be supported upon hard rubber bushings 84-85. Tape 21 with the recorded symbols facing upwards enters the device between guide rollers 23 and 70 (Fig. 9). It then passes along a tape guideway 86, to which a reflecting mirror 27 may be pivotally secured at 88 and 87. Tape guideway 86 and mirror 27 may form a part of a bracket 89 secured to base 82 by machine screws 90. After passing along tape guideway 86 where projection has taken place, tape 21 "rides" over thimble 59, around a direction changer 33, and passes between tape drawing roller 14, and spring arm roller 37. Rollers 14 and 37 may be milled or knurled to insure a firm grip on tape 21. The tape may be disposed of in any convenient manner. If a permanent record is desired, it may be wound upon a winding reel 38, having a detachable head plate 80. If a permanent record is not required, the tape 21 may be fed by gravity into a suitable waste basket (not shown). Figs. 9 and 10 illustrate one way of doing this. Spring arm 36, which is screw pivoted at 73, supports a mounting 76 for a guide plate 15. Tape 21 may be looped back over guide plate 15, by means of a looping guide wire 79, pivoted at 78, to guide wire 71. Guide wires 79 and 71 are secured to guide plate 15. After passing between guide plate 15 and guide wires 79 and 71, tape 21 feeds by gravity into a basket or other receptacle. Drawing roller 14 and grooved pulley 41 are both driven on shaft 49 of gear 48. Grooved pul-

ley 41, drives pulley 39 of winding reel 38, by means of belt 40.

Many variations of the inventive concept will occur to those skilled in the art. Figs. 11, 12 and 13 illustrate one such variation. Tape 21 is drawn by tape drawing roller 14 over a series of guide rollers 11. Roller 72 of lever arm 91 loops the slack tape (Fig. 11). When tape 21 stops feeding, arm 91 rises as the loop of slack tape is stored on a winding reel 38 (see Fig. 10). Arm 91, shaft 10, 5 collar 92, and spring lever 93, move in unison. Collar 96 is rotatably mounted on drive shaft 50. Main spring 56 is anchored to worm 53 and in an anchoring hole 97 of collar 96. Main spring 56 15 under normal tension binds on main shaft 50 and revolves with the shaft to turn worm 53 and collar 96. Auxiliary spring 94 normally allows collar 94 to revolve, thus allowing worm 53 to drive gear 48, to permit tape drawing roller 14 20 to take up the slack in tape 21. When the slack tape is taken up, arm 91 moves shaft 92 and spring lever 93 so as to bind auxiliary spring 94 on collar 96, to prevent collar 96 from turning. The continued rotation of drive shaft 50 imparts 25 counter-tension to main spring 56 which disengages from the drive shaft and ceases to revolve. Worm 53 and gear 48 now stop moving, and drive shaft 50 runs free. As soon as tape 21 becomes slack again, lever arm 91 moves downwards, auxiliary spring 94 releases collar 96, which turns 30 on shaft 50 to permit main spring 56 to resume its normal tension and bind on shaft 50, whereupon shaft 50, main spring 56, worm 53, gear 48 and collar 96 revolve together.

It should be understood that shaft 49 is geared 35 to drive tape drawing roller 14 so that it will draw tape 21 faster than ticker 20 can deliver the tape when operating at maximum speed. By this arrangement, in the embodiments of the invention shown in Figs. 1 to 10, tape 21 is never slack 40 enough to form a loop. Even when ticker 20 is operating at maximum speed tape 21 "rides" over thimble 59, the tape under these conditions being neither taut nor slack. When ticker 20 stops even momentarily, tape 21 becomes semi-taut and hugs 45 a larger section of thimble 59 and with increased tension, thereby arresting the movement of the thimble to bring worm 53, gear 48 and drawing roller 14 to an immediate stop. The instant that ticker 20 records a symbol and advances the tape 50 even but a single step, thimble 59 turns under the action of the coiled springs to permit main spring 56 to grip continuously driven shaft 50 to drive gear 48, shaft 49, and drawing roller 14 long enough to take up the tape. This is an improvement 55 over devices of the prior art, wherein the time lag between the operation of the stock ticker and the re-operation of the tape take up mechanism is considerable, thus permitting the stock ticker to gain a considerable lead on the take up 60 mechanism before the latter commences to operate.

As my mechanism responds variously to changes in tape pressure applied to thimble 59, stopping under heavy pressure, moving slowly under light 65 pressure and faster when tape 21 rides free, my device may be said to be a variable speed device and in this respect differs from the devices of the prior art which are incapable of speed variation. By using auxiliary spring 60 to counter-act 70 main spring 56 to effect gradual starting and stopping, a cushioning effect in starting and stopping is obtained. By cushioning in this manner the speed of movement of tape 21 is progressively varied from zero through slow to fast to slow to 75

zero again, without any sudden jerking movement. This is very important because it eliminates any tendency to cause flickering of the images projected upon the projector screen. The elimination of flickering is very important in the satisfactory operation of projecting systems of this character.

When assembled in portable form substantially as shown in Fig. 9, my device can be placed so close to a stock ticker 20, that it will project the images of all but the last three or four quotations recorded on tape 21. This is a distinct improvement over the prior art devices which are invariably twelve or more quotations behind the ticker. My mechanism therefore substantially 15 reduces the interval of time which elapses between the recording and projecting of the stock quotation.

The snubber shown in Figs. 6, 7 and 8, may be used instead of guide rollers. The snubber is made from a flat piece of metal 98 rounded off to eliminate sharp corners. A single turn of tape passes around snubber 98. To retain the tape in position, a finger 99 is pivoted at 100, to the frame 101 on which snubber 98 is supported. A spring 25 catch 102 secures finger 99 in operative position. A guide finger 103 also serves to prevent tape 21 from working loose on snubber 98.

What is claimed is:

1. In a device of the character described for feeding recorded news by an intermittent step by step movement and in combination, a drive shaft, a coiled spring mounted on and normally gripping said shaft with sufficient tension to revolve therewith, means, operable under the influence of said 30 revolving spring, to remove slackness in the intermittently moving news sheet, and means operable responsive to the increased tension of the news sheet when slackness has been removed therefrom to hold one end of the coiled spring 35 stationary to impart counter tension to said spring to break its grip on said shaft thereby arresting the movement of the slackness removing means.

2. In a device of the character described for feeding a news sheet by an intermittent step by step movement and in combination, a driving shaft, a driven member, a coiled spring anchored by said driven member and normally gripping said shaft with sufficient tension to revolve therewith 40 and operate said driven member, means operable under control of the driven member to remove slackness from the intermittently moving news sheet, a collar rotatably mounted on said driving shaft and attached to one end of said coiled spring, and means including a thimble rotatable with and 45 relative to said collar operable responsive to the increased tension of the news sheet when slackness has been removed therefrom to retard the rotation of the collar to cause said spring to break its grip on said driving shaft and arrest the movement of the driven member.

3. A tape control mechanism for translating the intermittent step by step advance of the recorded tape into a progressive start-stop movement comprising, a continuously driven shaft, worm drive mechanism rotatably mounted on said shaft, a coiled spring anchored to said worm drive mechanism and mounted on and normally gripping said shaft with sufficient tension to revolve therewith 50 and rotate said worm drive mechanism, means operable under control of said worm driven mechanism to remove slackness from the recorded tape, a collar rotatably mounted on said continuously driven shaft for engaging the other end of said 55 coiled spring, and means rotated in contact with

the tape by said collar and operable by the increased tension of the recorded tape when slackness has been removed therefrom to retard the rotation of the collar thereby imparting sufficient counter-tension to the revolving spring to cause 5 said spring to break its grip on said continuously driven shaft thereby arresting the movement of the spring and of the worm drive mechanism.

4. A tape control mechanism for translating the intermittent step by step delivery of the recorded 10 tape into a progressive start-stop movement comprising, mechanism for variously moving the recorded tape to remove slackness therefrom, a continuously moving drive shaft, a coiled spring having one end secured to said tape moving mechanism, said spring being mounted on and normally gripping said drive shaft with sufficient tension to revolve therewith and operate said tape moving mechanism, and means normally rotated in contact with the tape by the drive shaft but held inoperative by increased frictional engagement with the tape when slackness has been removed therefrom, to impart counter-tension to the coiled spring, thereby causing said spring to break its grip on said continuously moving driving shaft 15 thereby arresting the movement of the spring and of the tape moving mechanism.

5. In a tape control mechanism and in combination, a drive shaft, a coiled spring mounted on and normally gripping said shaft with light 20 tension to revolve therewith, a tape drawer attached to said spring and revolving with said shaft under control of said spring to remove slackness from an intermittently operated news recording tape, a tape contacting thimble mounted 25 for rotation with said spring gripped shaft when the tape is running free, a collar rotatably mounted relative to said shaft and said thimble and attached to one end of the coiled spring, and means, carried by said thimble and operable responsive to 30 the tension exerted by the tape upon the thimble when slackness is removed from said tape, to reduce the speed of rotation of said collar relative to said shaft and impart counter-tension to 35 said spring, thereby breaking its grip on said shaft 40 and arresting the movement of the tape drawer.

6. In a tape control mechanism and in combination, a drive shaft, a main spring coiled about and normally gripping said shaft with light tension to revolve therewith, tape drawing mechanism operable under control of said shaft driven 50 main spring to remove slackness from an intermittently fed news recording tape, a thimble mounted for rotation under control of said shaft driven main spring, the surface of said thimble 55 being in contact with the running tape, an auxiliary spring for controlling rotation of said thimble when the tape is running free, and means, interconnecting said main and auxiliary springs and normally rotatable with said springs and said 60 thimble, operable in conjunction with said auxiliary spring responsive to tension exerted upon the thimble by the tape when slackness is removed therefrom, to impart counter-tension to said main spring to break its grip on said shaft and arrest 65 the movement of the tape drawing mechanism.

7. In a tape control mechanism and in combination, a drive shaft, a main spring coiled about and normally gripping said shaft with light tension to revolve therewith, tape drawing mechanism rotatable under control of said revolving 70 spring to remove slackness from an intermittently running news recording tape, a cylinder mounted for rotation under control of said shaft driven main spring, the surface of said cylinder being 75

in contact with the tape, an auxiliary spring for controlling rotation of said cylinder when the tape is running free, and a collar interconnecting said main and auxiliary springs, and rotatably mounted relative to said cylinder and said springs and operable under control of said auxiliary spring responsive to tension exerted by the tape upon the surface of the cylinder when slackness is removed from the tape, to impart counter-tension to said main spring sufficient to break its grip on said shaft and arrest the movement of the tape drawing mechanism.

8. In a tape control mechanism and in combination, a drive shaft, a main spring coiled about and normally gripping said shaft with sufficient tension to revolve therewith, a worm driven tape drawer operable under control of said shaft driven

main spring to remove slackness from an intermittently running news recording tape, a cylinder mounted for rotation under control of said rotating spring, the surface of said cylinder contacting the running tape, an auxiliary spring controlling the rotation of said cylinder, and a collar interconnecting said main and auxiliary springs and normally rotatable with said springs and said cylinder, said collar and auxiliary spring co-acting responsive to tension exerted upon the surface of the cylinder by the tape when slackness is removed therefrom, to impart counter-tension to said main spring to break its grip on said shaft thereby arresting the movement of the worm driven tape drawer.

FRANK E. ANDERSON.
